C. W. LEE

RAIL JOINT AND CHAIR

Filed Dec. 8, 1925

Inventor

C. W. Lee.

By *Charles W. Lee*
Attorney

UNITED STATES PATENT OFFICE.

CHARLES W. LEE, OF LOCK HAVEN, PENNSYLVANIA.

RAIL JOINT AND CHAIR.

Application filed December 8, 1925. Serial No. 74,069.

To all whom it may concern:

Be it known that I, CHARLES W. LEE, a citizen of the United States, residing at Lock Haven, in the county of Clinton and State of Pennsylvania, have invented certain new and useful Improvements in Rail Joints and Chairs; and I do hereby declare the following to be a full, clear, and exact description of the invention, such as will enable others skilled in the art to which it appertains to make and use the same.

The invention relates to means for joining the ends of railroad rails and supporting the joint on the ties and has for its object the provision of an improved means for effecting a railroad joint of the type using an interlocking structure by which the expansion and contraction of the rails is permitted and also improved chair for supporting the joint comprising an integral base with upwardly directed flanges shaped to engage the bases and webs of the rails and also provided with a depending extension to engage between adjacent ties to prevent creeping of the rails.

The invention will be described in detail hereinafter and will be found illustrated in the accompanying drawings, in which—

Figure 1 is a side view of the meeting end fragments of two rails, showing the improved joint chair in position between two adjacent ties,

Figure 2, a transverse sectional view of the joint on a plane indicated by the line 3-2 of Figure 1,

Figure 3, a side view of the meeting ends of the rails in an interlocked position, and

Figure 4, an end view of one of the rails.

In the drawings similar reference characters will be used to designate corresponding parts throughout the several views.

The joint chair comprises a base 1 having upwardly directed flanges 2 that are extended inwardly of the base as shown at 3 and then upwardly as shown at 4 on parallel planes, this configuration of the flanges providing for enclosing the bases and webs of the rails to be hereinafter described.

On the under side of the base 1 is a downwardly extending projection 5 that has its under surface curved as shown, said extension being adapted to seat between adjacent ties designated A, as shown in Figure 1.

It will be apparent that the rail chair may be used with rails of standard construction, but the invention also includes

an improved means for joining the meeting ends of the railroad rails consisting essentially of a scarf joint as shown in Figure 3 of the drawings. The two rails that are to be joined are designated B and B', respectively. The end of rail B is cut away as shown at 6 through the tread of the rail and the web to a line corresponding with the junction of the web and the base of the rail and a recess 7 formed in the web of the rail, and the end portion of the web is left forming an upstanding lug 8. The rail B' has its end adjacent to the rail hereinbefore described cut to remove its base, and a recess 9 is provided therein extending upwardly to the under side of the tread of the rail, a depending lug 10 being provided on the extremity of the rail. The lug 10 has its lower end expanded by outwardly inclining the sides thereof as shown at 11, this expanded portion serving to engage the inner walls of the flanges of the rail chair to hold the extremity of the rail B' from vibration.

The rails B and B' are provided with elongated openings 12 that align with openings 13 in the vertical portions 4 of the flanges 2 to receive the usual bolts for securing the rails in position, the elongated openings 12 permitting movement of the rails relatively to one another due to changes of temperature and to this end the lugs 8 and 10 are also formed narrower than the recesses 7 and 9 respectively.

To assemble the device, one of the rails, preferably rail B, is inserted through the joint chair so as to expose the recess 7, the other rail B' is then positioned so that tongue 10 is seated in the recess 7 and tongue 8 in recess 9, and the joint chair is then moved into the position shown in Figure 1 to cover the meeting ends of the rails.

It will be apparent that the rail joint and chair of the invention will securely hold the meeting ends of railroad rails from separation, the extension 5 of the base of the chair also preventing creeping of the rails as hereinbefore stated, and furthermore that close contact between the rails and the chair will form an adequate bond for the meeting ends of the rails when the rails are used in connection with electric railroad systems.

What is claimed is—

1. A rail joint comprising a pair of rail sections, each of said rail sections comprising

- a base, a web, and a tread, the tread of one section and a corresponding portion of the base of the other section being cut away, the web of the first mentioned section being 5 cut away remote from the end of the rail to the line of the base of the rail forming a recess and an upstanding lug at the end of the base of said section, the web of the other section being cut away remote from 10 the end of the section forming a recess and a depending lug at the end of the tread on said section, the lower end of said lug being expanded, said lugs being adapted to seat in said recesses and being narrower 15 than the recesses to permit expansion and contraction of the rail sections.
2. A rail joint and chair comprising in combination with the meeting ends of rail-
- road rails having interlocking lugs and recesses, the recesses being wider than the 20 lugs to permit endwise movement of the rails, and the rails provided with elongated openings, a chair to receive said rails including a base, upstanding flanges thereon shaped to fit the base and enclose the webs 25 of the rails, said flanges provided with oppositely disposed openings aligned with the openings in the rails, securing means engaged through said openings, and a depending extension on said base adapted to seat 30 between adjacent railroad ties to prevent longitudinal creeping of the rails.

In testimony whereof I affix my signature.

CHARLES W. LEE.
